UNITED STATES PATENT OFFICE.

HERBERT A. WALLACE, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed August 18, 1923. Serial No. 658,144.

My invention relates to railway traffic controlling apparatus, and particularly to apparatus of the type comprising train carried governing means controlled by energy 5 received from the trackway. More particularly my invention relates to the trackway portion of such apparatus.

I will describe several forms of railway traffic controlling apparatus comprising my 10 invention, and will then point out the novel features thereof in claims.

In the accompanying drawings, Fig. 1 is a diagrammatic view showing one form of apparatus embodying my invention. Fig. 2 15 is a view showing a modification of the apparatus shown in Fig. 1. Figs. 3, 4 and 5 are views showing further modifications of the apparatus shown in Figs. 1 and 2.

Similar reference characters refer to similar 20 parts in each of the several views.

Referring first to Fig. 1, the reference characters 1 and 1^a designate the track rails of a railroad over which traffic normally moves in the direction of the arrow. These 25 rails are divided, by means of insulated joints 2, into a plurality of insulated track sections A—B, B—C, etc. Each such section is provided with a signal designated by the reference character S with an exponent 30 corresponding to the location. As here shown these signals are of the three-position semaphore type, that is, each signal is provided with a blade which is capable of assuming three distinctive positions at 0, 35 45 and 90 angular degrees with respect to its mast, in which positions the signal displays a "proceed" indication, a "caution" indication, or a "stop" indication, respectively. As shown in the drawing, each 40 signal S is located adjacent the trackway at the entrance end of the associated section, though this particular location is not necessary. Each signal S is controlled by means not shown in the drawing and forming 45 no part of my present disclosure. It is enough to say that when the associated section is occupied, the signal indicates stop, when the associated section is unoccupied and the next section in advance is occupied, 50 the signal indicates caution, and when the associated section and the section next in advance are both unoccupied the signal displays a proceed indication.

Each section is further provided with a

track relay designated by the reference character R with an exponent corresponding to the location and connected across the rails adjacent the entrance end of the section. Each section is also provided with a suitable source of track circuit current here 55 shown as a track transformer designated by the reference character E with an exponent corresponding to the location. Referring particularly to section A—B, the primary 60 of track transformer E^B is constantly supplied with alternating current from an alternator D over line wires 7 and 7^a. The secondary 8 of transformer E^B is connected by means of wires 28 and 29 with a pole changer P^B operated by signal S^B. The 65 pole changer P^B is connected with the rails adjacent the exit end of section A—B. It is therefore clear that track circuit current of one relative polarity which I will term "normal" relative polarity is supplied to 70 the rails of section A—B when signal S^B is at clear or caution, whereas track circuit current of the other or reverse relative polarity is supplied to the rails of section A—B when signal S^B is at stop. Interposed 75 between one of the rails of the section A—B and the pole changer P^B is a reactor 40 one function of which is to limit the output of transformer E^B when its terminals are short circuited by the wheels and 80 axles of a passing train.

Each section is thus provided with a track circuit comprising the rails of the section, a track relay R, a pole changer P, a reactor 40 and the secondary 8 of a track 85 transformer E^B in series.

Each track relay R is provided with a polarizing winding 39 constantly supplied with alternating current from line wires 7 and 7^a over wires 37 and 38 and such relays 90 are therefore responsive to reversals of the relative polarity of the track circuit current.

Means are also provided for supplying a second alternating current to the rails of each section in parallel. This current I 100 will hereinafter term the "local" current and for this purpose I provide each section with a resistor 3 connected across the rails adjacent the entrance end of the section, a similar resistor 6 connected across the rails adjacent the exit end of the section, and two similar resistors 4 and 5 connected across the rails at an intermediate point in the 105

section. The ohmic resistance of these resistors is of such value that they do not shunt enough track circuit current to prevent energization of the track relays R by the track transformers E . The immediate source of local current is a local transformer designated by the reference character G with an exponent corresponding to the location, the primary 11 of each such transformer being constantly supplied with alternating current from line wires 7 and 7^a. Referring particularly now to section A—B, a local circuit passes from secondary 10 of local transformer G^B through wires 17 and 17^a, normal contact 16—16^a of track relay R^B , wire 15, resistor 5 in section A—B, through both rails of the section in parallel to resistor 6, thence through wire 14, contact 34 of circuit controller F^B operated by signal S^B , wire 14^a, normal contact 13—13^a of relay R^B , and wire 12 back to secondary 10 of transformer G^B . When relay R^B is energized in the reverse direction due to the presence of a train in the section to the right of C , reverse contacts 16—16^b and 13—13^b thereon will be closed and signal S^B will be at caution. This will not affect circuit controller F^B however and the circuit just traced will be closed except that reverse contacts 16—16^b and 13—13^b will be substituted for normal contacts 16—16^a and 13—13^a. When track relay R^B is de-energized however, due for example to the presence of a train in section B—C, the local circuit is closed from secondary 10 of local transformer G^B through wire 17, back contact 18 of relay R^B , wire 19, resistor 3 in section B—C, through the rails of the section to resistor 4 thence through wire 20, back contact 21 of relay R^B , and wire 12 back to secondary 10 of transformer G^B .

It is, therefore, clear that local current is supplied from local transformer G^B to section A—B between resistors 5 and 6 or to section B—C between resistors 3 and 4 according as relay R^B is energized in either direction, or de-energized.

Before proceeding further it should be pointed out that the trackway apparatus herein described is intended for co-operation with train carried governing apparatus in the following manner: When the train is on a portion of track supplied with track circuit current of normal relative polarity and also with local current, the governing apparatus receives a proceed indication which indicates that the train may proceed at any speed not in excess of some high speed as 65 miles per hour; when the train is on a portion of track supplied with track circuit current and also with local current, the relative polarity of one of which currents is reversed, the governing apparatus receives a caution indication which means that the train may proceed only at speeds not in

excess of some intermediate speed, as 35 miles per hour; but if the train occupies a portion of track from which the supply of either track circuit current or local current is for any reason interrupted, the governing apparatus receives a slow indication which indicates that the train can safely proceed only at some low speed as 15 miles per hour.

As shown in the drawing signal S^A is at proceed and track circuit current of normal relative polarity is therefore supplied to the rails of the section to the left of A . Relay R^A is energized and local current is therefore supplied to the rails of the section to the left of A between resistors 5 and 6. If now a train moving in the direction of the arrow enters the stretch of track shown in the drawing it will receive a proceed indication while in the section to the left of A . The train is therefore allowed to proceed at any rate below 65 miles per hour. As the train passes point A , the de-energization of relay R^A closes the local circuit for section A—B between resistors 3 and 4 and the train continues to receive a proceed indication. The operation of the trackway apparatus as the train passes through the remaining sections is exactly similar and will be readily understood without further description. I will now assume that a train occupies the section to the right of C and that a following train enters the stretch of track shown in the drawing. The following train is allowed to pass through the sections to the right of A and section A—B as before but the signal S^C is now at stop and the track circuit current supplied to section B—C is therefore of reverse relative polarity. Relay R^C is also de-energized so that the local circuit between resistors 5 and 6 of section B—C is broken. The following train therefore receives a caution indication after it passes point B . As the train passes resistor 5 in section B—C, the interruption of local current causes a slow indication to be received aboard the train and this indication continues as the train enters the section to the right of C due to the absence of track circuit current in this section.

Referring now to Fig. 2, I show a modification of my invention adapted for use where roadside signals are not employed. The apparatus is the same as that shown in Fig. 1, except that I eliminate circuit controller F from the local circuits, and accomplish the reversal of polarity of the track circuit current by means of a slow-acting relay associated with each track relay R and designated by the reference character K with an exponent corresponding to the location. Referring particularly to relay K^B this relay is provided with a circuit which passes from line wire 7^a, through wires 27 and 22, normal contact 23—23^a on

reverse contact 23—23^b of track relay R^B, wire 24, winding of relay K^B, and wires 25 and 26 back to line wire 7. It is, therefore, clear that pole changing relay 5 K^B is energized only when relay R^B is energized. The secondary 8 of track transformer E^B is then reversibly connected with the rails of section A—B by means of wires 28 and 29, a pole-changer comprising contacts 30 and 31 of relay K^B, and wires 32 and 33. Each relay K is slow-acting for the well known purpose of preventing operation of its pole-changing contacts during reversal of the associated track relay R.

10 The operation of the apparatus is the same as that of the apparatus shown in Fig. 1.

Under some conditions of operation it may be desirable to cause a train to receive 20 a caution indication before it reaches the entrance end of a caution section, that is, before it reaches the section next in rear of an occupied section. One means for accomplishing this result is shown in Fig. 3. In 25 this view the track circuits are the same as those illustrated in Fig. 1. Referring particularly to transformer G^B, one local circuit now passes from secondary 10 through wires 17 and 36, normal contact 30 16—16^a of relay R^B, wire 15, resistor 5 in section A—B, through the rails of section A—B to resistor 6, thence through wire 14, contact 34 of circuit controller F^B operated by signal S^B, wire 14^a, normal contact 35 13—13^a of relay R^B, and wires 41, 42 and 12 back to secondary 10 of transformer G^B. This circuit is closed only when relay R^B is energized in the normal direction, and the current in this circuit is of normal relative polarity. Another local circuit passes 40 from secondary 10 of transformer G^B through wires 17 and 43, reverse contact 13—13^b of relay R^B, wire 14^a, contact 34 of circuit controller F^B, wire 14, resistor 6 in section A—B, through the rails of the section to impedance 5, thence by wire 15, reverse contact 16—16^b of relay R^B, and wires 44, 42 and 12, back to secondary 10 of transformer G^B. This circuit is closed only 45 when relay R^B is energized in the reverse direction, and the current in this circuit is of reverse relative polarity. A third local circuit for section B—C between resistors 3 and 4 is the same as in Fig. 1 and is closed 50 only when relay R^B is de-energized.

The operation of the apparatus shown in Fig. 3 is the same as in Fig. 1 with the single exception that if a section, as the section to the right of C, is occupied by a 60 train, a following train will receive a caution indication at resistor 5 in section A—B due to the reversal of the relative polarity of the local current at that point. The train will then receive the slow indication as it 65 passes resistor 5 in section B—C.

If roadside signals are not in use the apparatus shown in Fig. 3 may be modified by substituting a slow acting pole changing relay K for the signal operated pole changer P as illustrated in Fig. 2.

70 Fig. 4 shows a modification of a portion of the apparatus shown in Fig. 3. For purposes of simplicity, only the apparatus associated with point B is shown, it being understood that the apparatus at other points in Fig. 3 could be similarly modified. The apparatus is the same as that shown in Fig. 3 except that the local circuits are controlled in part by circuit controller F^B instead of contacts of relay R^B. In Fig. 4 one local circuit passes from secondary 10 of transformer G^B, through wires 17 and 36, normal contact 75 16—16^a of relay R^B, wire 15, resistor 5 in section A—B, through the rails of the section to resistor 6, thence through wire 15, contact 34—45 of circuit controller F^B, and wires 47, 42 and 12, back to secondary 10 of transformer G^B. This circuit is closed only when relay R^B is energized in the normal direction and signal S^B is at proceed. 80 Another local circuit passes from secondary 10 of transformer G^B through wires 17 and 43, contact 34—46 of circuit controller F^B, wire 14, resistor 6 in section A—B, thence through the rails to resistor 5, and through 85 wire 15, reverse contact 16—16^b of relay R^B, and wires 44, 42 and 12 back to secondary 10 of transformer G^B. This circuit is closed only when relay R^B is energized in the reverse direction and signal S^B is at caution. 90 In all other respects the apparatus is the same as that shown in Fig. 3 and the operation is identical, the purpose of the modification being to effect a saving in the number of track relay contacts required for the 95 local circuits.

If it is desired that the train should receive a caution indication throughout the entire length of the second section in rear of an occupied section, thus accomplishing 100 what is known as "three block indication" it may be effected by the modification illustrated in Fig. 5. In this arrangement the pole-changer P^B controls the relative polarity of both track circuit and local currents and to accomplish this the primaries 9 and 11 of the track and local transformers, respectively, at point B for example, are connected in parallel and the pole-changer P^B 105 is interposed between such primaries and the line wires 7 and 7^a. This change has no effect on the operation of the track circuit, but the relative polarity of the current supplied by local transformer G^B is now reversed wherever signal S^B indicates stop. 110 One local circuit now passes from secondary 10 of local transformer G^B through wires 17, 48 and 56, normal contact 57—57^a of relay R^B, wires 55 and 50, resistor 3 in section 115 A—B, then through the rails to impedance 120 125 130 A—B, then through the rails to impedance

- 6, thence by wire 14, contact 34 of circuit controller F^B , wire 14^a, normal contact 13—13^a of relay R^B , and wires 41, 42 and 12 back to secondary 10 of transformer G^B .
 5 This circuit is closed only when relay R^B is energized by track circuit current of normal relative polarity. Another local circuit passes from secondary 10 of local transformer G^B , through wires 17, 48 and 43, reverse contact 13—13^b of relay R^B , wire 14^a, contact 34 of circuit controller F^B , wire 14, resistor 6 in section A—B, through the rails of the section to resistor 3, thence through wires 50 and 55, reverse contact 57—57^b of relay R^B , and wires 42 and 12 back to secondary 10 of transformer G^B . This circuit is closed only when relay R^B is energized by track circuit current of reverse relative polarity. When relay R^B is de-energized, a local circuit is completed which passes from secondary 10 of local transformer G^B , through wires 17 and 58, back contact 52 of relay R^B , wire 49, resistor 4 in section A—B, then through the rails of the section to resistor 3, thence by wires 50 and 51, back contact 58 of relay R^B and wires 54 and 12 back to secondary 10 of transformer F^B . It will be observed that with this arrangement, only one resistor 4 is required at an intermediate point in the section.
 As shown in the drawing the parts of the apparatus are in the conditions corresponding to the unoccupied condition of the track. It is clear, that under such circumstances a train will receive a proceed indication as it passes through this portion of track. I will now assume that a train occupies the section to the right of C. As a result signal S^C indicates stop, circuit controller F^C is open and pole-changer P^C is reversed. Relay R^C is de-energized, and section B—C is supplied with track circuit current of reverse relative polarity and with local current of normal relative polarity between resistors 3 and 4 but no local current is supplied to section B—C between resistors 4 and 6. Signal S^B is now at caution and circuit controller F^B is closed and pole-changer P^B is in the normal position. Relay R^B is energized in the reverse direction. As a result track circuit current of normal relative polarity is supplied to the rails of section A—B and local current of reverse relative polarity is supplied to the rails between resistors 3 and 6. The section to the left of point A is normal. I will now assume that a train moving in the direction of the arrow enters the stretch of track shown in the drawing. This train will receive a proceed indication as far as point A where the reversal of local current will cause the governing apparatus to receive a caution indication. At point B the relative polarity of both local and track circuit current is reversed but this does not affect the indica-

tion aboard the train and the caution indication is maintained as far as resistor 4 in section B—C where the interruption of the local current causes a stop indication to be received aboard the train.

If desired the number of relay contacts required for this arrangement may be reduced by utilizing the circuit controller contacts as shown in Fig. 4.

It should also be noticed that in the absence of roadside signals, a slow-acting pole changing relay may be substituted for the signal operated pole changer P as illustrated in Fig. 2.

Although I have herein shown and described only a few forms of railway traffic controlling apparatus embodying my invention, it is understood that various changes and modifications may be made therein within the scope of the appended claims without departing from the spirit and scope of my invention.

Having thus described my invention, what I claim is:

1. Railway traffic controlling apparatus comprising a plurality of consecutive sections of railway track, a source of track circuit current reversibly connected with each said section, a relay connected with the rails of each said section and responsive to the reversals in said current, and means for directly supplying local current to the rails in multiple of said sections from a single transformer secondary located adjacent the junction of each two adjoining sections.

2. Railway traffic controlling apparatus comprising a plurality of consecutive sections of railway track, and means for directly supplying local current to the rails in multiple of said sections from a single transformer secondary located adjacent the junction of each two adjoining sections.

3. Railway traffic controlling apparatus comprising a plurality of consecutive sections of railway track, and a single transformer secondary adjacent the junction of each two said sections for supplying local current at times to one of the associated sections and at other times to the other associated section.

4. Railway traffic controlling apparatus comprising two sections of railway track, and a single energy source for supplying local current of one relative polarity or the other to a portion of one of said sections and of a single relative polarity to a portion of the other said section.

5. In combination, a forward and a rear section of railway track, a track relay for said forward section, a source of local current, and means, controlled by said track relay for connecting said source with a portion of said forward section or for reversibly connecting said source with a portion of said rear section.

6. In combination, a forward and a rear section of railway track, a source of track circuit current for said forward section, means responsive to traffic conditions in advance for reversing the polarity of said current, a source of local current, and means responsive to such reversals of said track circuit current for at times connecting said source of local current with the rails in parallel of a portion of the said forward section and at other times reversibly connecting said source of local current with the rails in parallel of a portion of the said rear section.

15 7. In combination, a forward and a rear section of railway track, a source of track circuit current reversibly connected with the rails of said forward section, a signal for said forward section controlled by traffic conditions in advance, a track relay for said forward section, a source of local current, and means controlled by said signal and said relay for at times connecting said source of local current with the rails in parallel of a portion of the said rear section.

8. In combination, a forward and a rear section of railway track, a source of track circuit current for said forward section, means responsive to traffic conditions in advance for reversing the polarity of said current, a source of local current, and means responsive to such reversals of said track circuit current for at times connecting said source of local current with the rails in parallel of a portion of the said forward section and at other times connecting said source of local current with the rails in parallel of a portion of the said rear section.

9. In combination, a stretch of railway track divided into sections, a track relay for each section, means controlled by each track relay for supplying track circuit current of one relative polarity or the other to the rails of the section next in rear, a single source of local current adjacent each said track relay, means controlled by each track relay for supplying local current from the adjacent source to the associated section and for supplying local current of one relative polarity or the other to the section next in rear.

55 10. In combination, a plurality of successive sections of railway track, a source of local current for each section, means responsive to traffic conditions in each section for supplying local current to the rails of such section from the associated source and for supplying local current of one relative polarity or the other to the rails of the section next in rear from said associated source.

11. In combination, a forward and a rear section of railway track, a track circuit for

each section, a single transformer secondary constituting a source of local current, and means responsive to traffic conditions for supplying local current from said secondary to said forward section when such section is occupied and for supplying said rear section with local current from said secondary when said forward section is unoccupied.

12. In combination, a stretch of railway track divided into a plurality of successive sections, a signal for each section, a track relay for each section, means controlled by each signal for supplying the section next in rear with track circuit current of normal relative polarity when the signal indicates proceed or caution and with track circuit current of the other relative polarity when the signal indicates stop, a source of energy for each section; and means controlled by each track relay for supplying the associated section with local current of normal relative polarity from said source between the entrance end and an intermediate point in the section when such relay is de-energized, and for supplying the section next in rear with local current from said source between the exit end and an intermediate point in the section, the current being of normal or reverse relative polarity according as the relay is energized in the normal or reverse direction, respectively.

13. In combination, a stretch of railway track divided into a plurality of successive sections, a signal for each section, a track relay for each section, means controlled by each signal for supplying the section next in rear with track circuit current of normal relative polarity when the signal indicates proceed or caution and with track circuit current of the other relative polarity when the signal indicates stop, a source of energy for each section; and means controlled by each track relay for supplying the associated section with local current of normal relative polarity from said source between the entrance end and an intermediate point in the section when such relay is de-energized, and for supplying the section next in rear with local current of normal relative polarity from said source between the exit end and an intermediate point in the section when the relay is energized in the normal or reverse direction.

14. In combination, a stretch of railway track divided into a plurality of successive sections, a signal for each section, means controlled by each signal for supplying the section next in rear with track circuit current of normal relative polarity when the signal indicates caution or proceed and with track circuit current of reverse relative polarity when the signal indicates stop, a first contact operated by each such signal closed only when the signal indicates proceed, a second contact operated by each signal

closed only when the signal indicates caution, a source of local current for each section, means controlled by each track relay for supplying local current of normal relative polarity to the rails of the associated section from the associated source, means controlled by each said track relay and including said first contact on the associated signal for supplying local current of normal 10 relative polarity to the rails of the section

next in rear from the local transformer associated with such relay, and means controlled by each said track relay and including the said second contact on the associated signal for supplying local current of reverse 15 relative polarity to the rails of the section next in rear from the local transformer associated with such relay.

In testimony whereof I affix my signature.
HERBERT A. WALLACE.
